Attorney

UNITED STATES PATENT OFFICE.

MORGAN R. BUTLER, OF WAUKESHA, WISCONSIN.

MATERIAL-HANDLING EQUIPMENT.

Application filed July 26, 1922. Serial No. 577,585.

To all whom it may concern:

Be it known that I, MORGAN R. BUTLER, a citizen of the United States, and resident of Waukesha, in the county of Waukesha and State of Wisconsin, have invented new and useful Improvements in Material-Handling Equipments, of which the following is a description, reference being had to the accompanying drawing, which is a part of this specification.

This invention relates to certain new and useful improvements in material handling equipment and refers more particularly to a gate construction for controlling the supply of material to a measuring hopper.

In aggregate measuring hoppers, it is very essential to the successful mixing of the aggregate to accurately measure, each time, an equal amount of material and to this end it is desirable that the measuring hopper be filled flush with the gate to thus eliminate any possible variance.

In the structures of this character now most commonly employed, the desired result is not obtained, as many of them employ a hopper which is partly open at the top so that instead of closing through the material the gate merely pushes the material into the open part of the hopper and depends upon the tendency of the material to maintain a predetermined angle in the opened part to measure the contents.

Having the objections to the former type of devices of this character in mind, it is a primary object of my invention to provide a gate construction which is so designed as to permit the measuring hopper to be completely filled with material without preventing the closing of the gate member.

Another object of this invention resides in the provision of a device of the character described having a follower member which is yieldable upon closing movement of the gate member when material is jammed between the end thereof to thus permit the free and complete closing of the gate member.

It is another object of this invention to provide a transverse recess communicating with the passageway connecting a source of material supply with a measuring hopper

whereby all material jammed between the end of the gate member, when being closed, may be forced therein to facilitate the closing thereof.

A further object of this invention resides in the provision of means operable upon opening movement of the gate member to discharge all material in the transverse recess through the passageway.

This invention has for a still further object to provide an improved control gate so designed that one or more gate members may be actuated from a common operating lever.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawing, I have illustrated one complete example of the physical embodiment of my invention constructed according to the best mode I have so far devised for the practical application of the principles thereof, and in which:

Figure 1 is a side view of a pair of measuring hoppers equipped with gate members embodying my invention, parts thereof being broken away and in section to more clearly illustrate details of construction;

Figure 2 is a fragmentary perspective view of one of the gate constructions, parts thereof being broken away to more clearly illustrate structural details, and

Figure 3 is an enlarged detail view taken transversely through Figure 1 on the plane of line 3-3.

In aggregate measuring hoppers, it is desirable that they be arranged in batteries or pairs, one hopper of each pair measuring sand and the other gravel and in the accompanying drawing but one pair is illustrated, in which the numeral 5 represents a gravel measuring hopper and 6 a sand measuring hopper. The hoppers 5 and 6 are supported or suspended from two spaced

parallel channel beams 7 upon which are mounted sand and gravel bins 8 and 9 connectable with the measuring hoppers 5 and 6 by passageways 10 and 11 respectively.

5 The measuring hoppers are substantially the same in construction differing only in size and each consists of an upper hood or shell 12, the upper open end of which communicates with the adjacent passageway, an 10 intermediate shell or casing 13 which is telescoped over hood 12 and has its upper edge struck inwardly, as at 14, to limit its downward movement and a bottom shell or hopper part 15 having a discharge opening 15 which is normally closed by a door 16. The bottom section of each measuring hopper is equipped with lateral arms or lugs 17 which are slidably engageable with suspension rods 18 supported from beams 7, and 20 the capacity of the hoppers is readily adjusted by raising the lowermost section 15, the sections being secured in this position by suitable members 19.

Centrally mounted between beams 7, for 25 movement longitudinally thereof, is a gate member operating bar or rod 20, which is supported at intermediate points by rollers 21 journaled between U-shaped brackets or supports 22 the ends of which retain the bar 30 in proper alignment with the beams 7. Fixed to bar 20 in spaced relation by securing means 23 are two gate members 24 and 25 adapted for movement across passageways 10 and 11, respectively, to disconnect 35 hoppers 5 and 6 from the material supply bins 8 and 9, respectively, when bar 20 is shifted by a lever or other means, not shown.

Passageway 11 is formed by the inner walls of beams 7 and two spaced transverse 40 brace plates 26 and passageway 10 is formed by the inner walls of beams 7, a transverse brace plate 27, similar to plates 26, and a follower member 28. Plates 26 and 27 have central transverse slots or openings 28' therein, through which the gate members 45 pass and have a central recess 29 communicating with slot 28' for the reception of rod 20.

When the gate members are in closed position, gate 24 has one end projected through the slot in plate 27 and its other end extended into a transverse recess or pocket 30 communicating with passageway 10 and formed by top and bottom plates 31 connecting beams 7. Gate member 25 has its opposite ends extended into slots 28', when in closed position, and when opened is in the dotted line position illustrated in Figure 1.

60 Follower 28 has a central recess or opening 32 through which rod 20 passes and the opposite ends of the follower have guideways 33 therein which engage tracks or guides 34 in the form of angle irons secured 65 to the inner faces of beams 7. The follower

28 is freely slidable independent of rod 20 but is positively positioned adjacent the side of the passageway 10 opposite plate 27, as illustrated in Figure 1, when gate member 24 is in open position, by a stop 35 adjustably secured on rod 20 by a set screw 36.

In operation, when it is desired to fill the measuring hoppers, rod 20 is shifted to the right with reference to the drawing to position the gate members as illustrated in Figure 1, follower 28 being moved to its position illustrated in Figures 1 and 2 by the stop 35 to prevent material from entering recess 30.

When the measuring hoppers are full, which can be readily ascertained by the ceasing of the sound caused by the material passing from the supply bins, the operator shifts rod 20 to the left with reference to the drawing. Heretofore, difficulty in closing the gate members has been experienced for as gate member 24 nears closed position, the gravel becomes jammed between its end and the side of the passageway, thus preventing further closing and with this construction the follower 28 yields as the material becomes jammed between it and the gate end to thus permit free closing movement, the very small amount of material in the jam being forced into recess 30.

With this construction accurate measuring of the gravel is obtained as hopper 5 is completely filled each time and it is impossible for additional material to fall into the hopper as its contents are being discharged. When the gate members are again opened to fill the measuring hoppers, any material in recess 30 is discharged into hopper 5 by the follower 28 which pushes the material out of the recess as illustrated by the dotted lines in Figure 1. In the drawing, gate member 25 is illustrated as not equipped with a follower 28, as I find from experiment that the gate member may be readily closed through sand.

110 What I claim as my invention is:

1. A device of the character described, comprising a member provided with an opening, a gate member mounted for movement across the opening, a follower positioned adjacent the opening when the gate member is in open position and movable away from the opening as the gate member is closed, and a connection between the gate member and follower for moving the follower to its position adjacent the opening as the gate member is moved to open position.

115 2. A device of the character described, comprising a member provided with an opening, a gate member mounted for movement across the opening, a follower positioned adjacent the opening when the gate member is in open position, said follower being moved away from the opening by closing movement of the gate member jam-

ming material between it and the follower, and means coordinated with the gate member for positively returning the follower to its position adjacent the opening upon opening movement of the gate member.

3. A device of the character described, comprising a member provided with an opening, a gate member mounted for movement across the opening, an operating rod secured to the gate member for moving the same to and from closed position, a follower mounted on the operating rod, and means moving the follower to a position adjacent the opening when the gate member is moved to open position.

4. A device of the character described, comprising a member provided with an opening, a gate member mounted for movement across the opening, an operating rod secured to the gate member for moving the same to and from closed position, a follower mounted on the operating rod, and a stop on the operating rod and engageable with the follower to move the same to a position adjacent the opening upon movement of the gate member to open position.

5. A device of the character described, comprising a member having a discharge passage, a gate member mounted for movement across the discharge passage, said passage having a recess communicable therewith, and a follower movable into said recess and adapted to be positioned adjacent the discharge passage when the gate member is in open position.

6. A device of the character described, comprising a member having a discharge passage, a gate member mounted for movement across the discharge passage, said passage having a recess communicable therewith, and a follower movable into the recess and adapted to be positioned adjacent the discharge member when the gate member is in open position, the follower being moved into the recess upon closing movement of the gate member by material jammed between the follower and gate member.

7. In a device of the character described, the combination with a material supply hopper having a discharge opening, of a pair of beam members mounted one on each side of the discharge opening, a gate longitudinally slidably mounted between the beam members for movement across the discharge opening to close same, and a follower mounted for movement between the beam members and adapted to be positioned adjacent the discharge opening when the gate is in open position.

8. In a device of the character described, the combination with a material supply hopper having a discharge opening, of a pair of beam members mounted one on each side of the discharge opening, a gate longitudinally slidably mounted between the

beam members for movement across the discharge opening to close same, guides carried by the beam members, and a follower slidably mounted between the beam members on said guides and adapted to be positioned adjacent the discharge opening when the gate is in open position.

9. In a device of the character described, the combination with a material supply hopper having a discharge opening, of a pair of beam members mounted one on each side of the discharge opening, a gate longitudinally slidably mounted between the beam members for movement across the discharge opening to close same, guides carried by the beam members, and a follower slidably mounted between the beam members on said guides and adapted to be positioned adjacent the discharge opening when the gate is in open position, said guides providing means for maintaining the gate horizontal when in closed position.

10. In a device of the character described, the combination with a material supply hopper having a discharge opening, of a pair of beam members mounted one on each side of the discharge opening and extended beyond the discharge opening in opposite directions, a bottom plate connecting the beam members and terminating adjacent the discharge opening, an operating rod longitudinally, slidably mounted between the beam members, a gate carried by the operating rod and movable thereby to and from a position closing the discharge opening, a follower slidably mounted between the beam members, and means positioning the follower adjacent the discharge opening when the gate is moved to open position, the follower being moved over the bottom plate upon closing movement of the gate by material jammed between it and the gate.

11. In a device of the character described, the combination of a bin, a discharge passageway leading from the bin, a gate movable across the passageway into open and closing positions, the wall of the passageway toward which the gate closes being movable with the gate in closing, and means operable by the gate in its opening movement to return said movable wall to normal position.

12. In a device of the character described, the combination of a stationary bin, a measuring hopper fixed to the bin and connected at the top with the lower part of the bin by a passageway, a gate movable across the passageway into open and closing positions, the wall of the passageway toward which the gate closes being movable with the gate in closing, and means for returning said movable wall to normal position with the opening of the gate.

13. In a device of the character described, the combination of a bin, a passageway leading from the lower portion of the bin, a gate

- movable across the passageway into open and closed positions, the wall of the passageway toward which the gate closes being yieldable to move away from the passageway with the gate in closing and the path of said gate intersecting the plane of the yieldable wall at a medial point, and means for returning said yieldable wall to normal position with the opening of the gate.
- 10 14. In a device of the character described, the combination of a bin, a passageway leading from the lower portion of the bin, said passageway having a transverse recess com-

municable therewith, a gate movable across the passageway into open and closed positions, the wall of the passageway toward which the gate closes being movable with the gate in closing into the transverse recess, and means for returning said movable wall to normal position with the opening of the gate member, the return of the movable wall to normal position clearing said recess of any material therein.

In testimony whereof I affix my signature.

MORGAN R. BUTLER.
